UNITED STATES PATENT OFFICE.

HERMANN RIPPKE, OF OBER-FÄSCHKITTEL, NEAR OLBENDORF, PRUSSIA,
GERMANY.

FIELD-MOUSE TRAP.

SPECIFICATION forming part of Letters Patent No. 426,857, dated April 29, 1890.

Application filed October 14, 1889. Serial No. 326,926. (Model.)

To all whom it may concern:

Be it known that I, HERMANN RIPPKE, a subject of the King of Prussia, and a resident of Ober-Fäschkittel, near Olbendorf, in the 5 Kingdom of Prussia and Empire of Germany, have invented a new and useful Improvement in Field-Mouse Traps, of which the following is a full, clear, and exact description.

The invention has for its object the provision of a device for the destruction of field-mice; and it consists in the novel construction, arrangement, and combination of parts, all as hereinafter described and claimed.

Reference is to be had to the accompanying 15 drawings, forming a part of this specification, in which similar figures and letters of reference designate corresponding parts in all the views.

Figure 1 is a plan view of a field-mouse trap constructed in accordance with this invention and in open position. Fig. 2 is a 20 side elevation of the same. Fig. 3 is a plan view of the same in closed position; and Figs. 4 and 5 are detail views in plan and side elevation, respectively, of the trigger-plate of 25 the trap.

Referring to said drawings, *a* is a piece of wire of any desired length and proper diameter, having at its end 1 a small hook, which wire is bent at a right angle, as shown at 2, 30 and again approximately at a right angle, as shown at 3, describing small curves between said bends 2 and 3, is then bent to form a spring-ring from the bend 3 to the right-angular bend 4, extends thence horizontally over the portion 1, is then bent upon itself, as shown at 5, extends thence beneath the horizontal limb 4 5 to the point 6, where it is coiled to form a spiral spring 7, and is then extended upward at one side of the spring, 35 and its extremity, at which there is formed a hook, is engaged with a bend 8 in the said horizontal limb of the wire, all as best shown in Figs. 1 and 2 of the drawings, whereby firmness is given to the whole wire frame. In 40 connection with said frame is employed a trigger-plate *b*, the forward end of which is pointed, and in said end is provided an opening *A*, from the sides of which extend teeth *c d e f*, which are bent upward from the plate 45 and their ends turned inward over the opening, while at the other end of the plate are

cut or stamped other teeth *g* and *h*, which are bent downward from the plate and their ends turned inward, and at one side of the rear end of the plate is formed a projection, the 55 inner edge of which is turned downward to form a lip *i*. The plate *b* is attached to the wire *a* by means of a small ring *b'*, inserted at its corner opposite the lip *i* and adapted to engage the bend 2 of the wire and have 60 free movement on said wire.

To set the trap in open position, the limb 1 2, held by the force of the spring of the ring portion 3 4 in the position shown in Fig. 3, is carried to the position shown in Fig. 1, and 65 the trigger-plate *b* is so laid upon it that the lip *i* engages the inner face of the limb 4 5 of the wire, thus holding the limbs 1 2 and 4 5 apart and preventing them from springing together until the lip *i* is disengaged from the 70 latter-named limb. The point of the trigger-plate bears on the upper part of the wire *a*, the opening *A* in said plate then standing over the interior of the spring 7.

In setting the trap about one-half of the 75 spring 7 is placed in the mouse-hole so that it, so to speak, lines the same. The mouse in trying to get out of the hole must pass through the spring and enter the opening *A* in the trigger-plate, but in so doing will push against 80 the teeth surrounding said opening, thus raising the plate, whereupon the lip *i* is disengaged from the wire *a*, the trigger-plate then assuming the position shown in Fig. 3 of the drawings, and the limbs 1 2 and 4 5 spring 85 together about the mouse and crush and kill it. If the mouse should endeavor to pass in the direction of the rear of the trigger-plate, it would come in contact with the teeth *g h*, and if it attempts passage in the direction of 90 the front of the plate the point of the same would be raised, resulting in either case in disengaging the lip *i* and allowing the horizontal limbs of the wire to spring together.

To prevent displacement of the trap by 95 mouse-hunting animals and birds, a hook *k* is attached to the ring portion of the wire and pressed at its point into the ground.

Having thus described my invention, what I claim as new, and desire to secure by Letters Patent, is—

In a field-mouse trap, the combination, with

a frame consisting of a pair of opposing spring-
arms and a vertical spiral spring intervening
the length of said arms, of a plate attached
at its rear end to one of said arms, having a
5 pointed forward end, a toothed opening in
said end, teeth on its under surface near its
rear end, and a lip at its rear end adapted to
be detachably engaged with the other spring-

arm, substantially as shown and described,
for the purpose specified. 10

In witness whereof I have hereunto set my
hand in presence of two witnesses.

HERMANN RIPPKE.
